STOCKING BOX

Sidney P. Voice, Hewlett, N. Y., assignor to Gotham Hosiery Company, Inc., New York,
N. Y., a corporation of Delaware

Application August 19, 1950, Serial No. 11,855

Term of patent 14 years

(Cl. D58—12.6)

To all whom it may concern:

Be it known that I, Sidney P. Voice, a citizen of the United States of America, residing at Hewlett, Long Island, State of New York, have invented a new, original, and ornamental Design for a Stocking Box, as shown in the enclosed drawings in which:

The drawing is shaded in parts to indicate color, it being understood that portions of each area not shaded are of the same color as the adjacent shaded portions.

I claim:

The ornamental design for a stocking box as shown and described.

SIDNEY P. VOICE.
